UNITED STATES PATENT OFFICE.

FREDERICK L. FULDAUER, OF CLEVELAND, OHIO, ASSIGNOR TO AMERICAN STOVE COMPANY, OF ST. LOUIS, MISSOURI, A CORPORATION OF NEW JERSEY.

OIL-FEED CONTROLLER.

1,383,926.

Specification of Letters Patent.

Patented July 5, 1921.

Application filed November 19, 1920. Serial No. 425,124.

To all whom it may concern:

Be it known that I, FREDERICK L. FULDAUER, a citizen of United States, residing at 5017 Perkins Ave., Cleveland, in the 5 county of Cuyahoga and State of Ohio, have invented certain new and useful Improvements in Oil-Feed Controllers, of which the following is a specification, reference being had therein to the accompanying drawing.

10 This invention relates to improvements in oil feed controllers, for controlling and regulating the flow of oil to the burner trough of a wickless blue flame oil stove.

It is well known to persons skilled in this 15 art, that a wickless blue flame oil stove comprises a trough containing a lighting member, in which trough the oil is fed and vaporized and the vapor passes upward between concentrically arranged perforated combustion tubes through which air passes and mixes with the vapor between the tubes, whereby a smokeless blue flame issues from 20 between the upper ends of the combustion tubes, the flame usually used in stoves for 25 cooking purposes.

In this form of burner, the height of the 30 flame is controlled by the level of the oil in the burner trough, and the amount of oil fed to the trough, which controls the rate and amount of vaporization of the oil taking 35 place in the trough.

In this form of burner, means is provided 40 for maintaining a maximum amount of oil level in the trough for maintaining a full flame, and the flow of the oil to the trough 45 has been controlled in two ways.

One form of control is a needle valve located in the oil feed conduit for controlling 40 the flow of the oil to the trough and thereby regulating the depth of oil in the trough and regulating the rate of flow of the oil to the 45 trough.

Another way of controlling the amount of oil maintained in the trough is by having the 45 oil level adjustable from maximum to minimum, or by moving the trough vertically in respect to a fixed oil level, whereby the oil level in the trough is regulated from maximum to minimum.

50 My improvement is applied to a burner in which both the trough and the oil level are fixed in respect to each other, and to control the flow of oil to the trough by an improved oil controller located in the conduit between 55 the trough and the oil level supply.

Heretofore, where the flow of oil to the trough is controlled by means located in the conduit between the trough and the oil supply, a needle valve has been practically the universal means for controlling the flow of 60 the oil.

A wickless blue flame oil burner after being heated up is very sensitive to the slightest variation in the amount of oil supplied to the trough and it has been difficult for the 65 mechanical unskilled persons who operate the burners, to accurately control the flow of the oil and thereby the flame of the burner; and in the use of the needle valve it has not been possible to quickly extinguish the burner, 70 because when the valve is closed the trough contains a certain amount of oil which must be consumed before the burner is extinguished.

75 My improvement comprises a regulating means which is located in the oil supply conduit so constructed that the flow of the oil is not so suddenly or sensitively controlled, whereby unskilled operators can evenly control the flow of oil to maintain the desired 80 height of flame, and whereby the burner is quickly extinguished by rapidly draining the trough of the oil contained therein at the time it is desired to extinguish it.

85 In the accompanying drawings, I have illustrated some of the mechanical expressions of means for carrying out my present improvement, in which—

Figure 1 is a vertical section of a stove frame showing my improvement applied 90 thereto.

Fig. 2 is a vertical section taken through the burner and my present improvement, showing the controller located in the oil feed conduit, the control being shown in full open 95 position.

Fig. 3 is a vertical sectional view of my improvement, showing it in closed position.

Fig. 4 is a similar sectional view to Fig. 3, showing the control partially open. 100

Fig. 5 is a detached side elevation of the movable controlling member, looking at the inlet side thereof.

Fig. 6 is a view similar to Fig. 5, looking at the outlet side thereof. 105

Fig. 7 is a vertical section, showing a modification of the controlling member, shown in partial open position.

Fig. 8 is a detached elevation showing a dial to coöperate with the pointer. 110

Fig. 9 is a view at right angles to Fig. 8, a portion of the trough being shown in section.

Referring now to the drawings, in which like reference numerals are applied to the same parts of my improvement, A is the burner; B my improved oil controlling and regulating device, C the maintained oil level supply; D the stove frame, and E the oil supply conduit which is common to a plurality of burners.

The burner A comprises the usual inner and outer perforated combustion tubes 1 and 2, the usual form of trough 3 which contains the usual form of lighting member 4, the operation of all of which is fully understood by those skilled in the art.

The oil supply level tube C may be of any of the well-known constructions for that purpose, which is so-well understood by those skilled in this art that it is unnecessary to show any specific form. This oil supply level C is connected with an oil supply conduit E, which is in communication with the trough of one or more wickless blue flame burners, and this supply conduit includes my improved oil feed controller B.

The form of my oil feed controller, shown in Figs. 2 to 6, inclusive, is one mechanical expression of my present improvement. This mechanical embodiment of my improvement comprises an outer member 5 and an inner member 6, and these members are relatively movable for controlling the oil supply. As here shown, the outer member 5 is in the form of a cylinder or tube and the inner member 6 is in the form of a movable valve or plunger. The cylinder 5 is considerably longer than the inner valve 6, and these last-mentioned members are made relatively movable in the form here shown by having the valve 6 move longitudinally in the cylinder 5. This is accomplished by connecting a rod 7 to the upper end of the valve 6, which extends through the upper end of the cylinder and provided with cogs 8. A shaft or rotatable rod 9 is suitably mounted on bearings 10 carried by the upper end of the cylinder 5 and this rod carries a pinion 11, meshing with the cogs 8. This rod 9 is rotated by a suitable handle 12, and the rod carries a pointer 13 coöperating with a suitable dial 14, for indicating the relative position of the valve 6 in the cylinder 5, for controlling the flow of the oil to the trough 3. The bottom of the trough 3 communicates with the cylinder 5, intermediate its ends, through a suitable conduit 15 and the cylinder 5 communicates with the oil supply pipe E, through a conduit 16, and a suitable conduit connection 17. The conduit 16 is in a different horizontal plane from the conduit 15, in the form here shown, and is in a plane below the conduit 15.

The valve 6 has a longitudinal opening 18, the upper portion of which has an outlet opening 19 and the lower portion an inlet opening 20. The outlet opening 19 is adapted to register with the conduit 15 and the inlet opening to register with the conduit 16.

The outer surface of the valve 6 is provided with a tapered recess 21, having its largest end communicate with the opening 20. This recess 21 is gradually decreased in depth and width from its lower to its upper end 22.

Attention is called to the fact that the cylinder 5 extends above the oil level, and, in fact, in the form here shown above the top of the trough 3, which forms a chamber 23 above the valve 6.

In Fig. 2, the valve 6 is shown in its wide open position. In Fig. 3 the valve is shown in its closed position, and in this latter position the upper end of the valve is considerably below the conduit 15, which forms a chamber 24 between the upper end of the valve 6 and the horizontal plane of the bottom of the trough 3 and, in fact, considerably below the lower end of the conduit 15. This chamber 24 performs an important function in my present improvement.

The operation of the parts thus far described is as follows:

When the burner is to be lighted, the pointer 13 will be turned to open position, as indicated on the dial 14, through the medium of the handle 12, and this lowers the valve 6 to open position, as shown in Fig. 2. Oil then flows through the conduit 16 into the valve opening 18, through the valve outlet 19 to the conduit 15 and there-through into the trough 3. The oil rises in the trough to the oil level. The outer or both of the combustion tubes are lifted from the trough and the upper end of the lighting member 4 which has become saturated with oil is lighted as is an ordinary wick. The combustion sections are then each placed on the trough and the burner begins to heat up to vaporize the oil in the trough, producing a smokeless blue flame at the top of the combustion tubes in a manner well known. When the burner is in operation, the supply of oil to the trough is controlled by moving the valve 6 downward. As the valve 6 is moved downward, the flow of oil through the valve is slowly graduated by reason of the tapered recess 21, and it is found in practice that in this way the flow of oil can be graduated to a nicety and refinement, which cannot be practically accomplished by a needle valve, which is the usual controlling device in the oil supply conduit of blue flame oil stoves.

It will be understood that this tapered recess 21 may be of any desired length to suit the conditions. The valve 6 and the recess 21 are shown substantially full-sized in Figs. 130

5 and 6, and this size of recess is found in practice to be efficient in enabling the mechanical unskilled users to adjust the flame of the burner to a degree which is not possible with the ordinary needle valve in the hands of unskilled persons. The construction also avoids the necessity of the stuffing box which must be used around the stem of a needle valve, as is well understood to persons skilled in this art.

Another feature of my improvement is to enable the burner to be quickly extinguished. This is accomplished by reason of the fact that when the parts are turned to closed position, as in Fig. 3, a chamber 24 is formed above the valve 6 into which oil quickly drains from the trough 3, so that there is no oil left in the trough to be consumed when the valve is in its closed position.

20 To permit the oil to flow through the valve 6 into the conduit 15, when the valve is elevated, for instance, to the position shown in Fig. 4 for reducing the flow of oil, through the intervention of the tapered recess 21, the outlet side of the valve 6 is provided with a vertical passage-way 25, with an open top and its lower end communicating with the outlet opening 19. By this construction when the valve 6 is lowered sufficiently to carry the outlet opening 19 out of communication with the conduit 15, communication is established between the opening 19 and conduit 15 by the passage 25. The same result, of course, could be accomplished by elongating the opening upward, but I find the construction of the passage-way 25 to be the most desirable way of accomplishing the above-described result.

With the valve 6 in the open position, as shown in Fig. 2, the lower end of the valve 6 is above the bottom of the cylinder 5, forming a chamber 26 into which oil seeps around the valve, and when that occurs, if permitted to remain, it would interfere with the downward movement of the valve. To provide an outlet for any oil seepage into the chamber 26 when the valve 6 is moved downward, I provide a pipe 27 which has its lower end 28 in communication with the bottom of the cylinder 5, and its upper end 29 in communication with the conduit 16 and thereby with the supply pipe E. By reason of this construction when the valve 6 moves downward in the cylinder 5, any oil 55 in the bottom of the cylinder is forced through the pipe 29 into the supply pipe E, thus permitting the valve to move downward to its closed position, as shown in Fig. 3. When the valve 6 is in its downward closed position, its lower end will close the lower end 28 of the pipe 27, as shown in Fig. 3. Preferably, this pipe 27 has its upper end 30 above the oil level.

By means of this construction, the amount 65 of flow of oil to the burner trough can be

regulated to a nicety in the hands of the ordinary user and thus obtain the desired height of flame, and accomplishes a quick extinguishment of the burner when the valve is in closed position.

70 In Fig. 7 I have shown one modification, in that the tapered recess 21 extends around the valve 6, as shown at 21^a in Fig. 7. This is shown, however, only as illustrating a construction that may facilitate the forming of 75 the tapered recess. Its operation is identically the same as the form of recess shown in other figures of the drawings.

I wish it to be understood that variations 80 may be made in the construction of the parts without departing from the spirit and scope of my invention.

I desire it also to be understood that other means may be used than that here shown, for moving the controlling members 5 and 6 in 85 relation to each other, without departing from my invention.

The dial 14 is secured to the member 5, by means of a suitable screw 31, as shown in Fig. 9. This dial co-operates with the 90 pointer 13, for the purpose of indicating to the operator the position of the pointer.

For the purpose of lifting the combustion sections 1 and 2, any suitable form of lifting rod 32 engages a diaphragm 33, within the 95 inner tube 1, and extends down below the trough 3. A lever 33 is intermediately pivoted to the member 5 at 34, the inner end 35 of the lever engaging the lower end of the rod 32, and the outer end of the lever extends through a bayonet slot 35, formed in the lower portion of a downward extension 36 from the dial 14. The outer end of the lever 33 is provided with any suitable form 100 of handle 37. The combustion sections are 105 lifted by this rod for the purpose of igniting the lighting member 4, and by means of the bayonet slot 35, the lever can be locked to hold the combustion sections out of contact with the trough when it is not being 110 operated for the purpose of preventing accumulation of oil on the combustion section by capillation from the trough, the reason for which is well understood to those skilled in this art.

115 Having thus described my invention, what I claim and desire to secure by Letters Patent is:

1. A controller for oil burners, comprising an oil conduit, a controller located in the 120 conduit comprising two members, one movable in respect to the other, one of said members having an oil passage tapered toward its closed position, for the purpose described.

2. A controller for oil burners, comprising a supply conduit, a controller located therein comprising two members, one movable in respect to the other, one of said members provided with an oil passage gradually 130

tapered in the direction toward its closed position.

3. The combination with a burner trough, of an oil supply conduit, a controller within the conduit, the controller comprising a vertical cylinder, a valve longitudinally movable in the cylinder to open and closed positions, the valve having a longitudinal opening with upper and lower openings communicating therewith, the cylinder having inlet and outlet openings registering with the upper and lower openings of the valve when the latter is in open position, the valve and cylinder relatively movable, one of said members having a longitudinally extending tapered recess in communication with one of its said openings, for the purpose described.

4. The combination with a burner trough, of an oil supply conduit, an oil controller located in the conduit, the controller comprising a cylinder, a movable valve within the cylinder, the parts movable to open and closed positions, the valve and cylinder having inlet and outlet openings out of line with but registering when in open position, one of the members having a tapered recess communicating with the adjacent opening of the other member as it moves to closed position, for the purpose described.

5. The combination with a burner trough, of an oil supply conduit, an oil controller located within the conduit, the controller comprising a cylinder and a valve longitudinally movable in the cylinder, the cylinder having upper and lower openings, the valve having a longitudinal opening with upper and lower openings adapted to register with the cylinder openings when the valve is in open position, the valve having its outer face provided with a tapered opening which extends in a direction away from the valve movement to closed position, for the purpose described.

45. 6. The combination with a burner trough, of an oil supply conduit, an oil controller located in the conduit, the controller comprising a vertical cylinder and a valve inclosed and longitudinally movable therein to open and closed positions, the valve and cylinder having inlet and outlet openings out of line but registering when the valve is in open position, the valve having its outer face provided with a recess tapering upward, the lower end of the recess communicating with the lower opening of the valve, for the purpose described.

7. The combination with a burner trough, of an oil conduit, a controller in the conduit, a controller comprising a vertical cylinder and a valve inclosed and longitudinally movable therein to open and closed positions, the valve and cylinder having upper and lower openings registering when the valve is in open position, the valve having

in its upper face a recess communicating with its lower opening, the recess decreasing in depth and width to its outer end, for the purpose described.

8. The combination with a burner trough, of an oil conduit, a controller in the conduit, the controller comprising a vertical elongated cylinder, the vertically elongated valve longitudinally movable in the cylinder to open and closed positions, the valve and cylinder having upper openings in communication when the valve is in open and closed positions, the valve and cylinder having lower registering openings when the valve is in open position, the valve having in its outer surface a recess extending upward from its lower opening, the recess decreasing in its area from its lower to its upper end, for the purpose described.

9. In a construction such as defined in claim 1, the valve having a longitudinal opening, a laterally extending opening at its upper end and a laterally extending opening at its lower end, the valve having in its outer surface an upwardly extending recess in communication with the upper opening and in its outer surface an upwardly tapered recess in communication with its lower opening.

10. The combination with a burner trough, of an oil controller of the type described, comprising relatively movable members having inlet and outlet openings movable to open and closed positions, one of said members having a chamber placed into communication with the burner trough when the members are in closed position, whereby the oil flows from the trough into said chamber, for the purpose described.

11. The combination with a burner trough, of an oil supply conduit, a controller in the conduit comprising a cylinder and a valve relatively movable to open and closed positions, the valve arranged in the cylinder to form upper and lower chambers in the cylinder when the valve is in open position, the valve adapted to place the trough into communication with one of the chambers when the valve is in closed position, for the purpose described.

12. The combination with a burner trough, of a conduit in communication with the trough and comprising a cylinder having upper and lower openings, a valve in the cylinder having a vertically arranged passage with upper and lower laterally extending openings arranged to communicate with the said cylinder openings when the valve is in an open position and to close them when in a closed position.

13. The combination with a burner trough of an oil supply controller, comprising a cylinder, a valve longitudinally movable therein to closed and open positions, the cylinder having a chamber thrown into com-

munication with the trough when the valve is in its closed position, for the purpose described.

14. The combination with a burner trough 5 of an oil supply controller, comprising a cylinder in communication with the trough, the valve and cylinder having oil supply passages, the valve movable to open and closed positions for controlling the oil supply 10 passage, the cylinder having a chamber in communication with the trough when the valve is moved to closed position, for the purpose described.

15. The combination with a burner trough, 15 of a burner comprising a cylinder having communication with the trough, a valve in the cylinder, the valve and cylinder having

inlet and outlet openings, the valve movable downward to closed position, and placing the cylinder in communication with the 20 trough when in its downward closed position, for the purpose described.

16. The combination with the burner trough, of an oil supply conduit, a controller therein comprising a cylinder and a valve, 25 the valve shorter than the cylinder and movable longitudinally therein to open and closed positions, and a communication between the lower end of the cylinder and the oil supply conduit, for the purpose described. 30

In testimony whereof I hereunto affix my signature.

FREDERICK L. FULDAUER.
